UNITED STATES PATENT OFFICE.

ALBERT PECK, OF NEW YORK, N. Y.

DESIGN FOR A PAPER COLLAR.

Specification forming part of Design No. 2,205, dated October 17, 1865.

To all whom it may concern:

Be it known that I, ALBERT PECK, of the city, county, and State of New York, have invented a new and original Design for Paper Collars; and I do hereby declare that the following is a full, clear, and exact description thereof, which will enable others to understand and adapt the design, reference being had to the accompanying drawings, making a part of this specification.

My invention consists in the design of two embossed or raised heads at certain distances apart and running parallel with each other around the flap of the collar, having indentations along their edges, the whole giving to a paper collar an ornamental appearance.

In the accompanying drawings, Figure 1 is a front view of a collar with my design upon it. Fig. 2 is a transverse vertical section taken in the plane of the line x x , Fig. 1.

A represents a paper turn-down collar, which may be of any desired pattern. Around this collar, commencing in front at the fold

and turning clear round the flap, are the beads a a' . These are made by embossing or otherwise stamping the collar, so as to make the raised line, as shown in Fig. 2. These beads a a' run parallel with each other, the bead a being the outer one and placed near the edge of the collar, and the bead a' a short distance inside of this, as shown in Fig. 1. On each side of these beads there is a line of indentations, b b' , which follow the beads their whole length, as shown clearly in Fig. 1. These beads and the indentations on each side give to a paper collar a tasty and ornamental appearance.

What I claim, and desire to secure by Letters Patent, is—

The design for paper collars herein shown and described.

ALBERT PECK.
